UNITED STATES PATENT OFFICE.

WILLIAM TEMPLIN, OF GLENELLYN, ILLINOIS.

STAND FOR BOOKS.

1,096,575.

Specification of Letters Patent.

Patented May 12, 1914.

Application filed February 24, 1913. Serial No. 750,049.

To all whom it may concern:

Be it known that I, WILLIAM TEMPLIN, a citizen of the United States, residing at Glenellyn, in the county of Dupage and State of Illinois, have invented certain new and useful Improvements in Stands for Books, of which the following is a specification.

This invention relates more particularly to stands which are adapted to support books, and which have means adapted to coact with engaging devices on the book covers for locking or fastening the books in position, being in substance a division of my former application, Serial No. 715,569.

The objects of this invention are to provide a stand with a simple and efficient fastening device for holding a book in position thereon, in such manner that the book may have sufficient movement to enable the leaves to be readily turned, and to provide such other novel features of construction as will appear from the following description.

In the accompanying drawings illustrating my invention; Figure 1 is a side view of the top of a stand showing a book supported thereon and held by my improved fastener, the leaves of the book in this and other figures being omitted for convenience in illustration; Fig. 2 is a plan view of the parts shown in Fig. 1, a portion of the book being broken away to show the construction of the fastening device; Fig. 3 is a view similar to Fig. 1, showing a slightly modified form of construction; and, Figs. 4 and 5 are details of the fastener shown in Fig. 3.

As illustrated in these drawings, 6 indicates the top of the table or stand for supporting a book 7, the upper surface of this stand being slanted so as to hold the book in convenient position for observation, and for the further purpose of preventing the stand from being used with other books than those provided with the proper fastening devices. I prefer to make the top 6 of frame work or skeleton construction, so that the same is not particularly adaptable for other uses than supporting a book. At the lower edge of the top 6, I provide chains or flexible connections 5, which have their inner ends secured to the top, and their outer ends secured to clips 8. These clips may be made in various forms for engagement with the lower edges of the book covers 7. For instance, as shown in Figs. 1 and 2,

the clip is bent at a substantially right angle, and one arm 9 is provided with an opening 10, which is adapted to fit over a catch 11, secured to the book cover 7. The catch 11 has a raised hook-like portion which is adapted to pass through the opening 10 and engages with the upper end of the arm 9, while the lower edge of the book cover 7 presses against the downwardly extending arm of the clip 8. Ordinarily, I prefer to provide two of such fastening devices, one at either end of the top 6 so as to engage with both of the covers of the book when the book is in open position, thereby serving to hold the book in open position, as well as supporting it on the stand. The flexible connection between the top and the covers permits the leaves to be readily turned.

In the modified form of construction shown in Figs. 3 to 5, the clips 12 are made approximately the same shape as the clips 8, but instead of having an opening therethrough, I provide them with notches or slots 13 in the ends of the upper arms 14. The book cover 15 is provided with a hook or catch 16, which has its raised portion 17 projecting toward the lower edge of the book, and which is adapted to take over the end of the arm 14 at the bottom of the notch 13 when the book cover 15 is moved down to locking position. In the first form of device the portion of the catch 11 which engages with the book cover is preferably counter-sunk in order to allow the arm 9 to lie against the upper surface of the cover, but in this modified form of construction it is not necessary to counter-sink the hook or catch 16, as the portion thereof which engages with the book cover fits within the slot 13. In both instances it will be noted that the fastening is accomplished by the relative sliding movement between the clips and the catches on the book covers.

Having thus described my invention, which however, I do not wish to limit to the exact construction described herein, except as specified in the following claims, what I claim and desire to secure by Letters Patent is:

1. The combination with a stand, of a flexible member secured to said stand, a bent strip secured to said member and adapted to engage with the lower edge of a book placed on the stand, and a catch on said book for engagement with said member.

2. The combination with a stand having
a frame work top, of flexible members se-
cured to one side of said top, metallic strips
secured to said members and bent to en-
5 gage with the edge of a book cover and hav-
ing slots or openings in the opposite ends
thereof, a book, and catches on said book

adapted to fit in said openings and engage
with said metallic strips.

WILLIAM TEMPLIN.
